UNITED STATES PATENT OFFICE.

ALEXANDER KELLEY, OF WILMINGTON, DELAWARE.

PAVING-BLOCK.

No. 870,889.

Specification of Letters Patent.

Patented Nov. 12, 1907.

Application filed January 23, 1907. Serial No. 353,595.

To all whom it may concern:

Be it known that I, ALEXANDER KELLEY, a citizen of the United States, residing at Wilmington, county of Newcastle, and State of Delaware, have invented a certain new and useful Improvement in Paving-Blocks, of which the following is a specification.

My invention relates to a new and useful improvement in paving blocks, and has for its object to provide a simple and effective block which will fit into the flange 10 of a street railway rail so that the rail will sustain the pressure put upon the blocks fitted therein, thus preventing the sagging down of the blocks and maintaining an even surface with the surface of the rails.

Another advantage of my invention is to make these 15 blocks interlocking and reversible, so that when one surface has worn they may be reversed and relaid, presenting a new wearing surface.

With these ends in view, this invention consists in the details of construction and combination of elements 20 hereinafter set forth and then specifically designated by the claims.

In order that those skilled in the art to which this invention appertains may understand how to make and use the same, I will describe its construction in detail, 25 referring by letter to the accompanying drawing forming a part of this specification, in which—

Figure 1 is a perspective of a portion of a street railway track showing my improved blocks fitted thereto. Fig. 2 is a detail perspective view of my improved paving 30 block showing the groove to permit the passage of the stay rod.

Referring to these drawings E represents one form of my improved paving block, which has formed therewith the tongue E', adapted to fit between the base and 35 top flanges of the rail, as clearly shown in Fig. 1, forming a firm support for the block, so that the weight of vehicles upon the upper surface of the blocks will not cause them to sag, and as their upper surface will be maintained on a level with the top flanges of the rail,

vehicles may pass over the rails without the jar and 40 twisting which is occasioned when the ordinary paving blocks sag down below the surface of the rails.

The blocks may have grooves F formed in their ends so as to permit the passage of the stay rods between the 45 rails.

By the use of my improved block the upper inner flange of a railway rail may be made considerably less in width than those now in use, since the block being flush therewith will serve the purpose of permitting wagon traction without the necessity of using the wide 50 flange and thus save considerable weight and cost of the rails.

Where a branch line or switch runs into the main line a block of the shape at M, in Fig. 1 may be used both sides of which would have tongues formed thereon for 55 fitting between the flanges of each rail.

My improved paving blocks are made of any suitable material that may be molded or cut such as stone or cement.

Of course I do not wish to be limited to the exact contour of the blocks, as the gist of my invention rests in the broad idea of providing a block having a tongue central of the body adapted to fit between the flanges of a rail so as to bring the surface of the block flush with the upper surface of the rail and receive a support from 60 the bottom flange of said rail.

Having thus fully described my invention, what I claim as new and useful, is—

In combination with the rails of a street railway a paving block having a tongue formed therewith adapted to fit 70 between the flanges of the rail and a groove formed in its end adapted to cooperate with a similar groove in an adjacent block and a rod to pass through said grooves as specified.

In testimony whereof, I have hereunto affixed my signature in the presence of two subscribing witnesses.

ALEXANDER KELLEY.
